UNITED STATES PATENT OFFICE.

THEODORE J. SMULSKI, OF CHICAGO, ILLINOIS, ASSIGNOR TO THE MILEOMETER COMPANY, OF CHICAGO, ILLINOIS, A CORPORATION OF ILLINOIS.

ROAD RECORDER AND INDICATOR.

Application filed January 3, 1921. Serial No. 434,544.

To all whom it may concern:

Be it known that I, THEODORE J. SMULSKI, a citizen of Poland, residing at Chicago, in the county of Cook and State of Illinois, have invented certain new and useful Improvements in a Road Recorder and Indicator, of which the following is a description.

This invention relates to improvements in road indicators of the type used in conjunction with vehicles, such as automobiles, and which facilitates driving through unfamiliar territory. By referring to the indicator, the driver may be constantly informed as to the characteristics of the locality in which he may happen to be, as the indicator provides a continuous record, map or the like of any portion of the tour. The invention has among its objects the production of a device of the kind described that is convenient, simple, compact, durable, efficient, adjustable and satisfactory for use wherever found applicable. More particularly the present invention relates to an improved indicator driving or actuating mechanism by means of which the instrument may be quickly and easily calibrated as required to accurately perform its functions. Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts,

Fig. 1 is a vertical sectional view;

Fig. 2 is a section taken substantially on line 2-2 of Fig. 1; and

Fig. 3 is an enlarged view of the driving means partly in section.

In order that my improved drive mechanism may be more clearly understood, I shall refer briefly to the cooperating parts of the mechanism, it being understood that many of the cooperating parts may be modified as found desirable.

Referring more particularly to the draw-

ings, A designates the indicator, comprising an enclosure or casing having a bottom wall 1, side walls 2 and 3, and a top 4, said top having openings therein to receive a sight panel 5, of glass or other suitable transparent material, through which the record may be viewed. The casing may be held together with any suitable means such as screws, latches, or the like, the top being adapted to be opened or taken off so that a record or tape may be removed from or inserted into the device.

Attached to the inside of the top 4, is a spring 6 which acts on a roller 7 to press it against a cooperating roller 8. Both the rollers are preferably milled or grooved on their peripheries and are of any suitable material, roll 7 being preferably of rubber, so that they may tightly engage a tape or record passing between them and feed the same.

A pair of spaced side plates 9 and 10 are positioned within the casing, one near each of the walls 2 and 3, both of the plates being apertured near their upper ends to receive the journals of the roller 8, one of the said journals extending outwardly through the casing wall 3 and having a suitable knurled thumb nut 11 at its outer extremity, whereby the roller may be manually rotated whenever it is desired to adjust the tape between the rolls.

The roller 8 may be driven in any suitable manner, as for instance by a gear 12 mounted near the end of the roller shaft. The gear 12 may be actuated through any suitable train of gearing (not shown), driven from the pinion 13 on shaft 14, said shaft 14 being rotatably journaled between the plates 9 and 10.

The reels of tape upon which the map or other indicia is marked are mounted inside the casing and are driven so that the tape is wound onto one or the other of the reels, depending upon the direction desired, the tape passing between the rollers 7 and 8, which pulls the tape positively from one reel and permits its winding onto the other reel. The reels are mounted on shafts driven by the pinion 13, through suitable gearing, as indicated at 15, Fig. 1.

My present invention relates particularly

to the means for driving shaft 14. As shown, friction disks 16 and 17 engage each other to drive shaft 14, the disk 16 being secured to the end of the shaft 14 opposite 5 to the pinion 13 and adapted to be automatically adjustable longitudinally of the shaft 14 by a spring 18 so that the disk is constantly urged against the friction surface of the driving disk 17. The disks 16 and 10 17 are preferably of different degrees of hardness, the disk 17 being the harder of the two, and it is also to be especially noted that the disk 17 is knurled or otherwise suitably roughened on its friction surface, while 15 the cooperating surface of the disk 16 is initially smooth, as shown, at its central portion, in Fig. 2. When in operation, the disk 17 will cut a track in the disk 16 complementary to its own knurled or roughened 20 surface and there will be no play or lost motion between these coacting roughened friction surfaces, for the cutting action of one disk upon the other produces a perfectly meshing drive surface.

25 Fig. 2 shows the cooperating disks, as they appear after use, illustrating the cutting action of the disk 17 upon the disk 16. The central area of the disk 16, which has not been in contact with the disk 17, retains its 30 initially smooth surface.

The driving element 17 is adjustably mounted on a drive shaft 19 so that the same may be raised or lowered, or that is, moved from or toward the center of the disk 16 so 35 as to vary the relative rate of speed or travel of the two disks. As shown, the disk or driving element 17 is mounted in a frame consisting of the plates 20 preferably secured together, and which are arranged to 40 travel on the guides 21 secured to the plate 22 and the bottom 1 of the casing. As shown, a threaded member 23 is rotatably carried by the casing and plate 22 and engages with a nut 23', forming a part of the frame 20. The 45 threaded member 23 is provided with an operating head 24. Obviously, as the member 23 is turned, the same causes the frame 20 to travel on the guides 21. The shaft 19 upon which the disk 17 is slidably mounted 50 projects to the exterior of the casing as indicated at 25 and may be connected to a part of the vehicle running gear, for example to one of the wheels.

In operation, when the device is assembled, disk 16 initially is substantially smooth, as previously mentioned, the cooperating teeth upon the same being cut by the disks 17 when the device is operated. Obviously, on vehicles the speed of the shaft 19 transmitted 60 from the wheels depends upon the size of the wheel; consequently the device may be adjusted for different sizes of wheels, thereby making it applicable for different makes of vehicles. It is also found that the 65 speed of the shaft 19 transmitted from the

wheels may vary with different degrees of tire inflation, and also all tires are not the same size. Road conditions may also have an effect on the driving of the shaft 19 from one of the wheels, requiring a calibration of 70 the instrument. With the driving mechanism herein described, the instrument may be calibrated from time to time, and even on different trips or during the same trip, by merely adjusting the position of the disk 75 17 by means of the head 24 of the threaded member 23. The instrument may be checked against known distances, or by means of the time and speedometer indications. If it is found that the road indicator is reading 80 too fast, that is advancing the tape too fast, the driving mechanism may be adjusted to correct this, and the same is true if the mechanism is not indicating fast enough.

Having thus described my invention, it is 85 obvious that various immaterial modifications may be made in the same without departing from the spirit of my invention; hence I do not wish to be understood as limiting myself to the exact form, construction, 90 arrangement and combination of parts herein shown and described, or uses mentioned.

What I claim as new and desire to secure by Letters Patent is:

1. In a device of the character described 95 and in combination, an indicator driving element, and drive means for driving said indicator driving element, said drive means comprising a driving and a driven element adapted to frictionally contact with each 100 other, one of said drive elements having a roughened friction surface and the other of said driven elements having a smooth friction surface.

2. In a device of the character described 105 and in combination, an indicator driving element, and adjustable drive means for driving said indicator driving element, said drive means comprising a driving and a 110 driven element adapted to frictionally contact with each other, one of said drive elements having a roughened friction surface and the other of said driven elements having initially a smooth friction surface.

3. In a device of the character described 115 and in combination, a tape driving element, and means for actuating said tape driving element, said means comprising a driving member having a roughened surface, and a driven member having initially a relatively 120 smooth surface, said driving and driven members being adapted to frictionally contact with each other whereby the driver will form a complementary roughened engaging surface on said driven member.

4. In a device of the character described 125 and in combination, a tape driving element, and adjustable means for positively actuating said tape driving element, said means comprising a driving member having a 130

roughened surface, and a driven member having initially a relatively smooth surface, said driving and driven members being adapted to frictionally contact with each other whereby the driver will form a complementary roughened engaging surface on said driven member.

5. In a device of the character described and in combination, a tape supporting and driving element, and adjustable means for actuating said supporting element, said means comprising a driving member and a driven member adapted to frictionally engage with each other, said driving member having a roughened surface and composed of a material relatively harder than that of the friction surface of said driven member, whereby said driving member will form a roughened engaging surface on said driven member.

10. In a device of the character described and in combination, an indicator driving element, and means for driving said tape driving element, said means comprising a 15 driving member having a roughened surface and a driven member initially having a relatively smooth surface, said driving and driven members being adjustable to vary the speed of the driven member and adapted 20 to frictionally contact with each other,

whereby the driver will form a complementary roughened engaging surface on said driven members.

15. In a device of the character described and in combination, a reel supporting element, and means for driving said reel supporting element, said means comprising a driving member and a driven member adapted to frictionally engage with each other and adjustable to vary the speed of 25 the driven members, said driving member having a roughened surface and composed of material relatively harder than that of the friction surface of said driven member, whereby said driving member will form a 30 complementary roughened engaging surface on said driven member.

20. In a road guide device of the kind described and in combination, tape carrying mechanism and adjustable driving mechanism therefor, whereby the instrument may be calibrated to control the travel of the tape.

25. In testimony whereof, I have hereunto signed my name in the presence of two sub- 55 scribing witnesses.

THEODORE J. SMULSKI.
